UNITED STATES PATENT OFFICE.

JULIAN J. NIELSEN, OF CHICAGO, ILLINOIS, ASSIGNOR TO JOHN CUTHBERT, OF CHICAGO, ILLINOIS.

WIRE COILING AND CLAMPING DEVICE.

1,241,756.

Specification of Letters Patent.

Patented Oct. 2, 1917.

Application filed December 18, 1915. Serial No. 67,539.

To all whom it may concern:

Be it known that I, JULIAN J. NIELSEN, a citizen of the United States, residing at Chicago, in the county of Cook and State 5 of Illinois, have invented certain new and useful Improvements in Wire Coiling and Clamping Devices, of which the following is a specification.

My invention relates to means for coiling 10 a wire around the shank of a wire clamping member and subsequently clamping the wire in place by operation of said clamping member.

One of the objects of my invention is to 15 provide a wire coiling device for coiling the wire about a wire clamping screw and which is adaptable for use with standard screws without modification or change of any kind in the character of the screw.

Another object of my invention is to provide 20 a wire coiling member adapted to be rotated about the threaded clamping member and which is primarily operated to coil the wire about the shank of the clamping member, such as a screw, prior to the 25 subsequent rotation of the screw to clamp the wire which is permanently associated with the screw and which may be rotatable independently thereof.

Other and further objects of my invention 30 will become readily apparent to persons skilled in the art from a consideration of the following description when taken in conjunction with the drawings, wherein:—

Figure 1 is a plan view of one form of my wire clamping and binding device.

Fig. 2 is a section on line 2—2 of Fig. 1.

Fig. 3 is a blank of which the coiling device illustrated in Fig. 1 is made.

Fig. 4 is the device formed up from the blank.

Fig. 5 shows the coiling device as applied to a clamping screw.

Fig. 6 is a modification showing an elevation of a screw driver with wire coiling attachment and the screw and coiling device parts in section.

Fig. 7 is an elevation of the screw driver

attachment for rotating the wire coiling device.

Fig. 8 is a section taken on line 8—8 of Fig. 6.

In all the views the same reference characters are employed to indicate the same parts.

The embodiment of my invention is of the same general character as that disclosed in the application of John Cuthbert for wire coiling and clamping devices Serial No. 35,064 filed June 19th, 1915. In the aforesaid application the operation of coiling the wire about the shank of the associated clamping member is accomplished by rotation of the coiling and clamping member prior to its clamping action. In my invention the coiling member is a part separate from the clamping member and may be made rotatable independently of the clamping member.

In the drawings representing my invention I have shown two forms which my invention may take, merely to more clearly exemplify the fact that it is not to be confined to a single showing. It is capable, however, of further variation, not necessary to be shown and is limited only by the scope of the appended claims.

10 is a body or base, which may be of insulating material, such as a block of porcelain or the like, to which a wire binding screw is to be attached. 11 is an interiorly screw threaded sleeve, having a terminal flange, held in place by a screw 12 and washer 13 taking through an orifice 14, in the opposite side of the base. An enlarged washer 15 may, if desired, underlie the flange of the sleeve 11. The flange 11 and the washer 15 are perforated near the axis of the clamping member, as at 16, to insert the conducting wire 17 prior to being clamped. A clamping screw 18 is insertible in the screw threaded sleeve 11 and is the means for clamping the wire 17 between the head of the screw and the flange of the sleeve 11. Threaded over the screw 18 is a separable clamping member 19 having op-

positely downturned flanges 20 providing wire-engaging shoulders 21. The flange 20 should be preferably of length less than the diameter of the wire to be clamped. The 5 wire coiling member 19 is centrally perforated, as at 22, through which perforation the screw 18 passes. The clamping member is provided with means for engaging the device used to rotate the screw such, for instance, as one or more laterally extending fingers 23. Two such fingers are shown on opposite sides of the axis of the perforations 22. After the member 19 has been threaded over the clamping screw 18 the fingers 23 10 are bent up on either side of the screw slot.

To operate the devices shown in Figs. 1 to 5 inclusive the wire 17 is first threaded through the perforation of the block 10 and 20 through the perforations 16 made through the flange 11 and the washer 15, which perforations in the said devices register, and the end of the wire is extended beyond the shank of the screw 18 sufficiently to be coiled about said shank. At this time the screw 18 may be some distance out of the threaded sleeve 11 so as to permit the wire 17 to pass under the coiling member 19. A 25 screw driver is now inserted in the slot 24 of the screw 18 and between the fingers 23 of the coiling member on either side of the said slot and the screw and coiling device are thereby rotated. The contact of the screw driver, when it is sufficiently wide to 30 span the slot 24 and engage the fingers 23, rotates the coiling member 19 that coils the wire around the shank. The shoulders 20, one on either side of the shank of the screw, serve to hold the coil of the wire adjacent 35 to the shank and prevents its movement from the position in which it has been coiled. A narrower screw driver may now be inserted in the slot 24 of the screw, so that it will 40 not touch the fingers 23 and the screw may be further rotated independently of the coiling member to clamp the wire in position.

In the modified device shown in Figs. 6, 7 and 8, the clamping member is not necessarily provided with laterally extending fingers 23, for engagement with the screw driver to rotate said coiling member, but instead thereof sleeve 23' is placed upon the shank of the screw driver 25 and is axially 50 movable thereon, being limited only by the pin 26 which projects laterally from the screw driver. The sleeve 23 is provided with a slot 27 terminating in notches 28 at each end within which the pin 26 may be contained when moved out of the slot 27. The lower notch 28 is preferably somewhat larger than the upper one and when the sleeve is raised so that the pin is contained in the lower notch 28, the sleeve 23 is held above

the screw driver point 29. The sleeve 23 65 is cut away on either side on its lower end, as at 30, to provide a bifurcated end consisting of two points 31. When the sleeve 23 is in the position shown in Fig. 6, the points 31 engage opposite sides of the wire 70 coiling member 19 and upon rotation of the screw driver 25 the coiling member 19 engages the wire 17 and coils it around the shank of the screw 18. After the wire has thus been coiled in proper position, the 75 sleeve 23 is raised on the shank of the screw driver 29, upon which it is freely movable, in an axial direction until the lower notch 28 engages the pin 26, on the screw driver, and thereby the sleeve 23 is moved out of 80 the way of the point 29 of the screw driver and held in position thereon, after which the screw 18 may be rotated to wire clamping position, by means of the point 29 of the screw driver entering the slot 24, independently 85 of the wire coiling device.

Either form of the wire coiling member 19 or any equivalent thereof may be placed upon any of the standard screws, such as screw 18, and used in the manner described. 90

Having described my invention, what I claim is:

1. The combination with a rotatable wire clamping member, of a wire coiling member 95 detachably associated with the wire clamping member and having an abutment for engagement with a rotating tool, and a wire engaging and coiling projection thereon.

2. The combination with a rotatable wire clamping member, of a wire coiling member 100 detachably associated with the wire clamping member and comprising a flat body part, a wire engaging and coiling projection on the under side thereof, and lugs projecting in the opposite direction to provide a screw 105 driver receiving slot.

3. The combination with a wire clamping screw having a slotted head, of a wire coiling member detachably associated with the wire clamping screw and positioned to underlie the head thereof, a wire engaging and coiling shoulder on said member, and a part 110 projecting above the member into the path of the screw driver whereby to rotate said member when the screw is rotated.

4. A wire coiling member for the removal from and replacement on a clamping screw and rotatable independently thereof, comprising a part to underlie the head of a screw, a part in the path of the screw driver 120 whereby to rotate said device when the screw is rotated and a part to engage a wire to coil it about the shank of the screw, said screw driver engaging part permitting independent rotation of the screw.

5. The combination with a wire clamping screw having a slotted head, of a wire coiling member detachably associated with the

wire clamping screw and positioned to underlie the head thereof, a wire engaging and coiling shoulder on said member, and lugs integral with the said member and extending over the edges of the head at each side of the slot for engagement with a screw driver.

6. A wire coiling member for employment on a wire clamping screw comprising a plate to underlie the head of the screw having

means for engaging the screw rotating instrumentality and means to engage the wire to coil it about the screw shank.

In testimony whereof I hereunto set my hand in the presence of two subscribing witnesses.

JULIAN J. NIELSEN.
